UNITED STATES PATENT OFFICE.

WILLIAM L. BUTTS, OF NASHVILLE, TENNESSEE.

PUMP.

SPECIFICATION forming part of Letters Patent No. 398,938, dated March 5, 1889.

Application filed September 4, 1888. Serial No. 284,564. (No model.)

To all whom it may concern:

Be it known that I, WILLIAM L. BUTTS, a resident of Nashville, in the county of Davidson and State of Tennessee, have invented certain new and useful Improvements in Pumps; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention is an improvement in pumps, and is shown as applied to a lift-pump, though it is also applicable to a forcing-pump.

The object of the invention is to keep the water in the well pure and sweet by forcing air through the water at every operation of the piston-rod, thus preventing the water from souring or fouling.

In the drawings, Figure 1 is a sectional view of a pump embodying my invention. Fig. 2 is a vertical section of modification.

In the drawings, A represents the working cylinder, which may be submerged or above ground, and this contains the lift-valve a, which may be of ordinary construction. They are shown as connected with their seats to a hollow piston-rod, B, which is operated by a handle, such as shown in Fig. 2. The seat of the valves is in the form of a ring, as shown at c, and the outer periphery is provided with a suitable packing, which fits closely the inner periphery of the lifting-cylinder.

The pump-barrel is shown at C and extends a suitable distance down the well, where it is connected with a casting, D, provided with an offset, d, to which is connected a section-pipe, e, extending down into the well, its end being perforated to allow for the ingress of the water; also, connected to a branch of the casting D is a cylinder, f, down which the hollow piston-rod extends, carrying upon its end a disk, g, the open bottom end of the piston being covered by a check-valve, h. The bottom of the cylinder f has a cap-piece, G, covering it, and is in connection with the water of the well through openings in the bottom of the said cap-piece. Between these openings and the bottom of the cylinder f is a valve, i, held

against shoulders k by means of a spring, l, which thus prevents the water from flowing in the cylinder f.

In the operation of the pump as the piston-rod is reciprocated in its upward movement, the valves a, by exhausting the air, draw the water through the pipe e, casting D, and barrel C into the cylinder A, from whence it passes to the spout by lifting the valves a. In the downward movement of the piston, the cylinder f being filled with air through the hollow piston, the valve h being open as the piston moves upward, this air is prevented from escaping through the piston-rod by the valve h closing, and the only way of escape is by opening the valve i by reason of the air-pressure overcoming the pressure of the spring, and thus the air is discharged into the water and purifies and enlivens the same as it passes through to the outside air.

At the top of the suction-pipe e, I place a check-valve, 4, which is provided with an arm, 3, extending into line with a projection, 5, on the piston-rod, and when it is desired to entirely free the pump from water it is only necessary to throw up the pump-handle to its greatest extent, which will cause a projection, 5, to come in contact with the arm 3, thus lifting the valve 4 and draining the pump completely.

In Fig. 2 the pump is substantially the same as in Fig. 1 with the exception only that instead of having a separate suction-pipe, I make the main barrel of the pump serve as a suction-pipe by perforating it below the water-line and placing the air-forcing cylinder below it, as shown.

I claim as my invention—

1. In a pump, the combination, with the pump-barrel, of a piston and hollow piston-rod, valves carried by said rod for lifting the water, an inlet-valve, an air-chamber connected to the pump-barrel with its lower end below the water-line, and provided with an opening covered by a suitable valve between the chamber and outside water, and an opening also covered by a valve from the piston-rod to the air-chamber, substantially as described.

2. In combination with the pump-barrel, the hollow piston-rod carrying the lifting-valves, an inlet-valve, an air-chamber con-

nnected to the pump-barrel openings from said chamber to the surrounding water, a valve normally closing said openings, a disk carried on the lower end of the piston-rod, forming the piston of the air-chamber, and a valve covering the lower open end of the rod, substantially as described.

2. In combination with the piston-rod of a pump, carrying the lifting-valves, an inlet valve, and an air-cylinder connected to the pump-barrel, arranged below the water-line opening to the outside air through the hollow

piston-rod, protected from the water above by a closely-fitting disk carried on the end of the piston-rod, and protected from the water below by a spring-supported valve, substantially as described. 15

In testimony that I do claim the foregoing as my own I hereby affix my signature in presence of two witnesses.

WILLIAM L. BUTTS.
